DEVICES FOR APPLYING STOCKINGS OR THE LIKE

Diena Minnema, 159 Manchester Ave., North Haledon, N.J., and John Minnema, Jr., 36 Summit Ave., Hawthorne, N.J.

Filed Nov. 12, 1963, Ser. No. 322,622

2 Claims. (Cl. 223—111)

The present invention relates to devices for applying 10 stockings, or the like.

It is common knowledge that many aged or variously afflicted or disabled persons find it difficult or impossible to put on hose, as stockings, socks, etc., without aid from another person. Although this applies especially 15 to elastic or surgical stockings, or the like, it is true also in some cases regarding apparel hose. These difficulties commonly exist where persons cannot stoop or bend or can do so only with great discomfort.

An object of the present invention accordingly has been to provide a simple and inexpensive device by the use of which stockings, socks, elastic hose and the like may be drawn on without aid by persons, otherwise capable, who for any reason are unable to stoop or bend sufficiently to do this in the normal manner.

A further object has been to provide a stocking applying device which can be used by a person, unaided, not only to draw on hose, or the like, but also to remove the same, regardless of the type or style of hose involved.

A further object of the invention has been to provide a device of simple construction for applying stockings or the like which can be used repeatedly without injury to the stockings; which requires no accessory or cooperating additions or special parts secured or attached to the stockings; and which has no moving parts requiring maintenance or repair.

In general, a device according to my invention comprises an elongated relatively rigid handle or shaft conveniently including a hand hold at one end. A ring of rigid material, as metal, plastic, etc. is secured to the other end and positioned in a plane substantially normal to the longitudinal axis of the shaft or an extension thereof with the ring, in effect, extending laterally and offset from said end of the shaft. Said ring is provided with a plurality of angularly spaced prongs extending radially from one side of its plane and having their free ends rounded and their bases secured to said ring, said prongs being directed upwardly in a curved path to bring their free outer ends beyond and above the outer peripheral surface of said ring; and said outer ring surface extends outwardly beyond the outer surfaces of said base portions of the prongs where they join the ring. The arrangement of parts is such that in use the prongs and ring will support the leg portion of a stocking when arranged in a roll and closely engaging outer face portions of said prongs and with the unrolled ankle portions of the stocking bearing on said outer surface of the ring. As so arranged, the stocking is in position to readily receive the wearer's foot when inserted through the ring and may be unrolled in place on the wearer's leg as the device is pulled upwardly while the wearer's foot, thus engaged in the foot of the stocking, is resting on the floor or other support.

Other objects and distinctive features of the present invention not above referred to will appear from the following specification and claims and from the accompanying drawings wherein is shown a preferred embodiment thereof incorporated in a stocking applying device as described in said specification. The showing so made is not intended to be either exhaustive or as limiting the scope of the subject invention. The purpose here is to

2

illustrate the invention so that others skilled in the art may so fully understand it, its principles and applications, that they may embody it and adapt it in any of various forms appropriate to the attainment of any particular or appropriate purpose in use.

In the drawings:

FIG. 1 is a side elevation;

FIG. 2, a front elevation;

FIG. 3, a plan view from the line 3—3 on FIG. 2;

FIG. 4, a fragmentary side view on enlarged scale with parts broken away showing outer surface portions of the stocking applying device engaged by a rolled portion of a stocking leg preparatory to drawing the stocking onto the wearer's leg; and

FIG. 5, a plan view similar to FIG. 3 on enlarged scale with the rolled stocking applied to the ring as in FIG. 4 and showing a wearer's foot inserted through the ring and the rolled portion of the stocking and extending into the unrolled ankle and foot portions of the stocking preliminary to drawing the stocking upward to final unrolled position on the wearer's leg.

Referring to the drawings, an elongated shaft of relatively rigid material carries a ring 12 at its bottom end and, at its top end, FIG. 2, a handhold 11 whereof the 25 side and tip end surfaces are of rounded contour. In view of the intended manner of using this device, ring 12 is advantageously circular and of an inside diameter sufficient to permit easy passage of a person's foot, ankle and knee therethrough; and the shaft 10 is long enough to 30 enable a user, when gripping the handhold 11, to bring ring 12 into position under his foot without stooping or bending.

The shaft 10 extends upwardly, as seen in FIGS. 1 and 2, from ring 12 in a direction slightly inclined rearwardly, 35 as seen in FIG. 1, and slightly inclined laterally, as seen in FIG. 2 but with said ring disposed in a plane which is substantially normal to the shaft axis. The bottom end of shaft 10 includes a short connecting portion 13, FIG. 3, positioned substantially in the plane of ring 12 and which 40 extends inwardly from an inner surface portion of said ring. This arrangement produces an advantageous relationship of the parts where ring 12 and shaft 10 are formed from a single length of wirelike material, for example.

As shown more clearly in FIG. 3, ring 12 is fitted with 45 a plurality, as five, for example, of prongs 14, 14a, 14b, 14c and 14d, each having a rounded tip end. Prongs 14 and 14d are angularly spaced in opposite directions from shaft 10 approximately 60°. And adjacent ones of the 50 remaining prongs are also angularly spaced from each other approximately 60°.

As seen in FIG. 2, the bases of said prongs are secured 55 to ring 12 in such position that the outer or circumferential surface of ring 12 extends outwardly beyond said bases and lower end portions of the outwardly exposed surfaces of said prongs. However, as seen in FIG. 2, free end portions of each of the prongs extend upwardly and radially outwardly in a curved path, thus being arranged and adapted, as a group, to be engaged in use by inner surface portions of roll 16 of the stocking leg which is 60 thus supported in operative position to be applied to the user's leg. The shapes, positions and dimensions of said prongs 14, 14a, etc. are such that their outer end portions overlap and extend across roll 16 when the stocking is mounted in operative position encircling outer surface portions of ring 12 and said prongs, as seen in FIGS. 4 and 5.

In a typical case, as where a person's physical infirmity or disability prevents bending the legs or back, the device above described may advantageously be used in the following manner. The shaft 10 is held in position between the user's thighs or knees with ring 12 in up position, i.e.,

with prongs 14, 14a, etc. directed downwardly. The leg portion of the stocking, FIGS. 4 and 5, starting at the top edge, is rolled outwardly on itself to form roll 16 terminating approximately at or just above the ankle zone 15 of the stocking. Roll 16 is now engaged with the device in a position to snugly embrace outwardly exposed surface portions of prongs 14, 14a, etc. between the free ends thereof and ring 12. With roll 16 in this position, the upper end of the unrolled ankle portion 15 of the stocking embraces or is, in effect, stretched over ring 12 with the foot portion of the stocking, FIG. 5, hanging free. In this posture, the stocking is now engaged on the applying device in condition to receive the wearer's foot and to be drawn up and unrolled over the wearer's leg.

For this purpose, the user grasps handle 11 and brings ring 12 with the rolled stocking engaged thereon into a position under his foot, or so that he may now insert his foot, as in FIG. 5, through ring 12 and roll 16 into part 15 and the foot of the stocking. As shown in the drawings, prong 14d is advantageously distinguished by being colored, as red. The back seam, or similarly positioned part, of the rolled stocking is placed to approximately register with this prong. If the user now places or has his foot resting on the floor, he unrolls the stocking into normal wearing position around his leg by pulling shaft 10 upwardly to move ring 12 and the rolled portion of the stocking upwardly around his leg to the desired extent, or until roll 16 is unrolled, whereupon the stocking comes into normal applied condition on the user's leg and the top edge thereof disengages from ring 12 and 30 prongs 14, 14a etc. which may conveniently be pushed downwardly by shaft 10 and so disengaged from the user's leg and foot.

To remove a stocking or the like, the top end or handhold 11 of shaft 10 is inserted between the user's leg and the top edge of the stocking and is pushed downwardly. Thus, when the shaft 10 is pushed down a sufficient distance, handhold 11 enters the foot portion of the stocking; and continued downward advance thereof, enables the user, without aid, to disengage the stocking completely 40 from his leg and foot.

From the foregoing description considered in connection with the drawings, it appears that a device embodying my invention provides for aged or disabled persons, among other advantages, a mechanical aid of simple construction with no moving parts and capable of use without accessories or special devices applied to or used with the stockings or the like; which may be usefully employed with all usual kinds of apparel and elastic hose; and which may be used to pull on and remove stockings without bending the back or legs.

We claim:

1. Stocking applying device comprising an elongated shaft, a ring secured at one end thereof extending laterally therefrom in a plane substantially normal to the longitudinal axis of the shaft, a plurality of angularly spaced prongs on said ring disposed at one side of and extending upwardly from said plane, each of said prongs being of rounded surface contour at its sides and free end and secured at its base to said ring and curving radically outwardly to bring its free end beyond the periphery of said ring, the peripheral surface of the ring extending outwardly beyond the outwardly exposed surface of said base portions of the prongs adjacent to said ring.

2. Stocking applying and removing device according to claim 1 and wherein said shaft has a hand hold at its opposite end and the tip end and side surfaces of said handhold are of rounded contour surfaces.
